UNITED STATES PATENT OFFICE.

MURRAY BERTRAM HAMILTON, OF TORONTO, ONTARIO, CANADA.

NONSLIP DEVICE FOR HEELS OF LOW SHOES.

Application filed April 10, 1925. Serial No. 22,169.

To all whom it may concern:

Be it known that I, MURRAY BERTRAM HAMILTON, a subject of the King of Great Britain, and a resident of the city of Toronto, in the county of York, in the Province of Ontario, Canada, have invented certain new and useful Improvements in Nonslip Devices for Heels of Low Shoes, of which the following is the specification.

10 My invention relates to improvements in non-slip devices for heels of low shoes, and the object of the invention is to devise a simple device which will effectively prevent the slipping of the heel of the foot out of the heel of the shoe, and yet will be such as will provide an even flush surface against which the heel bears so that there will be no protruding part which will render the heel of the foot sore by continual rubbing contact, 15 and at the same time devise such a device as will be simple and less costly to manufacture, and it consists essentially of the arrangement and construction of parts as hereinafter more particularly explained.

20 Fig. 1 is a perspective view of a shoe showing the device applied thereto.

Fig. 2 is an enlarged perspective detail of my non-slip device incorporated in the shoe lining.

25 Fig. 3 is a similar view of Figure 2 showing the reverse side.

Fig. 4 is a sectional plan detail through the heel portion of a shoe.

30 In the drawings like characters of reference indicate corresponding parts in each figure.

1 indicates the shoe lining which is divid-

ed at the centre of the heel back, the divided ends 2 and 3 being spaced apart as clearly indicated in Figures 2 and 3, the edges so formed being preferably slightly concaved.

4 is an insert piece having a roughened outer face, the outer edges being convexed outward and secured to the edges 2 and 3 by a line of stitching forming a closed seam, the edges of which are moistened and spread back before the lining is inserted in the shoe, so as to form an even surface. The bottom of the insert piece 4 is preferably provided with a V notch 5 in order that it may fit evenly to the back of the shoe without any tendency to pucker.

By this construction it will be seen that the outer face of the insert roughened piece is formed flush so that it will be perfectly smooth against the heel of the wearer, so that there will be no protuberance which would tend to make sore or blister the wearer's heel by constant frictional contact thereagainst, and at the same time I have provided a construction which is far less costly to make, and can be manufactured in a minimum amount of time.

What I claim as my invention is:

In a low shoe, the combination with the shoe lining divided centrally of the heel back and having the divided ends spaced apart, and an insert piece having a roughened outer surface located and permanently held between the divided ends of the lining and having its outer surface flush with the outer surface of the lining.

MURRAY BERTRAM HAMILTON.
